DESIGN FOR A RANGE

John C. Rogers, Cicero, Ill., assignor to Crown
Stove Works, Cicero, Ill., a corporation of Illi-
nois

Application March 12, 1936, Serial No. 61,602

Term of patent 14 years

To all whom it may concern:

Be it known that I, John C. Rogers, a citizen of the United States, residing at Cicero, county of Cook, and State of Illinois, have invented a new, original, and ornamental Design for a Range, of which the following is a specification, reference being had to the accompanying drawing, forming a part thereof.

Figure 1 is a perspective view of a range em-

bodying my new design. The other end of the range is like that shown.

Figure 2 is a view similar to Figure 1, but showing the top cover in open position.

I claim:

The ornamental design for a range substantially as shown and described.

JOHN C. ROGERS.
